UNITED STATES PATENT OFFICE.

CHRISTIAN NYGAARD, OF MOOSE JAW, SASKATCHEWAN, CANADA.

SHOCKING-MACHINE.

1,297,394.

Specification of Letters Patent. Patented Mar. 18, 1919.

Application filed March 30, 1918. Serial No. 225,804.

To all whom it may concern:

Be it known that I, CHRISTIAN NYGAARD, of the city of Moose Jaw, in the Province of Saskatchewan, Canada, have invented certain new and useful Improvements in Shocking-Machines, of which the following is the specification.

The invention relates to improvements in shocking machines and the principal object 10 of the invention is to provide a machine to accompany the ordinary binding machine and which will receive the sheaves ejected from the deck of the binder, collect and form the sheaves into a shock and deposit the 15 shock butt down and establish it firmly on the ground and will then reset itself to receive further sheaves.

A further object of the invention is to 20 provide a machine which will compress the heads of the sheaves prior to depositing the stock whereby a good base is given the stock and the same will on such account be more firmly planted on the ground.

A still further object of the invention is 25 to construct a machine wherein the sheaf receiving and shock forming basket is free to pass back to accommodate the deposited stock, thereby preventing, to a great extent, the upsetting of the stock due to the forward travel of the machine.

With the above general and other minor 30 objects in view, which will become more apparent as the description proceeds, the invention consists essentially in the arrangement and construction of parts hereinafter more particularly described and later pointed out in the appended claims, reference being had to the accompanying drawings in which:—

40 Figure 1 represents a side view of the complete shocking machine in the normal or sheaf receiving position.

Fig. 2 represents a plan view of the same with certain parts of the binding machine 45 shown.

Fig. 3 represents a front view of the machine and part of the binding machine.

Fig. 4 represents a view similar to Fig. 1 but with the machine shown in the position 50 it takes just shortly after the shock has been deposited.

Fig. 5 represents a side view of part of the machine showing one of the basket hangers and adjoining parts.

Fig. 6 represents an enlarged detailed side 55 view of the clutch and associated parts with the clutch in engaged position.

Fig. 7 represents a view similar to Fig. 6 with the clutch in disengaged position.

Fig. 8 represents an enlarged detailed longitudinal sectional view through the pressure crank.

Fig. 9 represents a side view of the starting trip.

In the drawings like characters of reference indicate corresponding parts in the several figures.

In order that the shocking machine may be better understood I have considered it advisable to show the parts of the binding 70 machine with which it is associated, these being the binder frame 1 and deck 2, the shocker being attached to the binder frame in a location such that the conveyer thereof receives the sheaves delivered or ejected 75 from the deck. The shocking machine is now described in detail.

3 represents an open ended substantially rectangular main or under frame fitted with a rearwardly extending supporting caster 80 wheel 4 and provided forwardly with suitable bearings 5 and 6 which receive pivotally a cross shaft 7 on the outer end of which I mount a driving wheel 8 and a driving chain wheel 9 adapted to rotate with the 85 wheel 8. The inner side of the machine frame is fitted with extending arms 10 and 11 which are pivotally secured at 13 to the binder frame. Four corner posts 14, 15, 16 and 17 extend upwardly from the main 90 frame and support a top frame like structure comprising cross beams 18 and 19 and lengthwise extending beams 20 and 21.

From the above it will be apparent that the lower and upper frames together with 95 the corner posts form an open box like framework which framework is utilized to support and contain the sheaf receiving and shock forming basket 22.

This basket is of the ordinary form, being 100 somewhat cylindrical in shape although contracted at the rear end and provided with an open top 23 through which the sheaves are deposited to fill the basket. The basket is suspended by a yoke shaped supporting 105 shaft 24 which is permanently secured to the basket and has the ends thereof extending into short horizontally slanted supporting

stub shafts 25 and 26 which terminate in ball ends 27, the balls being received within sockets 28 and 29 presented by vertically disposed sleeves 30 and 31 slidably mounted on vertically disposed guide shafts or hangers 32 and 33 located at opposite sides of the framework and having their upper ends pivotally secured by pivot pins 34 to the members 20 and 21 of the top frame. The lower 10 ends of these guide shafts terminate short of the under frame so that they swing clear of the same.

At the front of the shocking machine I locate a counter shaft 35 carried in suitable 15 bearings 36 and 37 fastened to the corner posts 14 and 17. The counter shaft is fitted with a pair of spaced pulleys 38 and 39 fixed to the shaft and provided with extending winding cables, straps, cords or such like 40 and 41 which pass from the pulleys upwardly over guide pulleys 42 and 43 secured 20 to the top frame and then project downwardly and are permanently fastened to the sleeves.

25 From the above arrangement it will be obvious that when the counter shaft is turned in a clockwise direction the straps will wind on the pulleys and draw up the sleeves thereby raising the basket. The basket is retained in the horizontal sheaf receiving position by the action of a weight 44 secured to the rear end of it and causing it to tilt backwardly and the action of a stationary cross bar 45 secured to vertically 30 disposed carrier bars 46 and 46' spaced from the guide shafts but having the ends brought in and permanently fastened to the guide shafts.

To explain the above action it will be seen 40 by referring to Fig. 1 that the basket in the normal position is held up by the straps and is held in the horizontal position by the action of the weight tilting the rear end down against the bar 45. The counter shaft is 45 intermittently driven by the chain wheel 9 in the following way:—

47 is a chain wheel mounted rotatably on the outer end of the counter shaft and connected by means of a chain 47' to the chain 50 wheel 9. The chain wheel 47 is formed with a clutch member 48 which rotates with it and directly opposing the latter clutch member is a further clutch member 49 formed at the end of a sleeve 50 feathered as indicated 55 at 51 on the counter shaft. The sleeve is provided with a flange 52 and with an extending pin 53 and between the flange and the chain wheel 47 I locate a coiled spring 54 which acts to hold the sleeve back against the bearing 36 and with the clutch members disengaged.

To the adjoining corner post 14 I secure a 60 controlling cam 55 on which the pin operates and the said cam is provided with an inclined face 56 on which the pin rides and

which face spirals for approximately three-quarters of a revolution in a direction toward the gear wheel. The cam is also fitted with a disengaging trip 57 adapted in the rotation of the sleeve to catch the pin and throw it back to disengage the clutch members.

A more full description of this action will later be given.

In the normal or up position of the basket 75 it will be seen that it has a natural tendency to fall, swinging over on the bar, the sleeves sliding down. This natural tendency is overcome by providing the inner end of the counter shaft with an extending striker 58 80 which, in the up or normal position of the basket, is engaged by a bell crank 59 pivotally secured to the corner post 17. The bell crank normally engages the striker and to the bell crank I connect a link 60, the lower 85 end of which is secured to a crank 61 located at the outer end of an operating shaft 62 passing to the binder and fitted with any suitable appliance whereby the attendant of the binder can, when desired, rotate the 90 shaft.

From this it will be obvious that the basket is normally locked in the up position and that the attendant can by rotating the shaft 62 actuate the bell crank to release the 95 striker and allow the filled basket to fall by gravity. A spring 63 is provided to reset the bell crank.

64 represents a vertically disposed pressure plate located at the front end of the 100 basket and carried by the cross member 19 of the top frame.

The counter shaft is supplied with a pressure crank 65 which, in the rotation of the counter shaft, is adapted to engage with the 105 lower end of the pressure plate and force the same inwardly toward the basket, this action being utilized to compress the sheaves within the basket as the basket passes to dumping position.

The pressure crank comprises a sleeve 66 fitted with a spring pressed plunger 67, the outer end of which carries a roller 68.

In order to deliver the sheaves to the basket, which has a more or less elevated position in respect to the deck, I provide an elevator 69 which has the lower end supported from the bars 10 and 11 and the upper end supported from the top frame of the shocker. This elevator is provided with two endless 115 conveyors 70 and 71 suitably driven from the binder mechanism and arranged such that the sheaves delivered or ejected from the deck are passed upwardly between the conveyors and ejected from the conveyors over 120 a chute 72 into the basket.

I have not entered into the details of the construction of the elevator as it is of ordinary construction and is only shown as a means for elevating the sheaves from the 130

deck to a position where they can be delivered through the open top of the basket into the same.

When this machine is in use and the basket is in the normal position the sheaves passed from the deck are delivered by the elevator to the basket. As soon as the attendant considers that enough sheaves are in the basket to make a proper shock he activates the shaft 62 to release the striker. Immediately this occurs the basket drops by gravity until it takes initially a position as shown in dotted outline in Fig. 1. In dropping it rocks over, so to speak, on the bar 45 which remains stationary at this time. As the basket drops the straps unwind and rotate through the pulleys 38 and 39 the counter shaft, in the present instance, approximately three-quarters of a revolution. As the counter shaft rotates the pressure crank turns over to bring the roller 68 into engagement with the pressure plate and force the pressure plate inwardly to effect the compression of the heads of the sheaves 25 within the basket and the consequent spreading of the butt of the stook.

In rotating the three-quarters of a revolution as above stated the counter shaft causes the sleeve 50 to rotate three-quarters of a revolution and makes the pin 53 climb the face 56 with the result that when the basket has dropped the full distance the face 56 of the cam has moved the pin so that the clutch members are brought into engagement. During this action the spring 54 is compressed. Immediately the clutch members engage the shaft is driven in the opposite direction by the chain wheel 47 which is rotated at all times by the wheel 9 and the pin 40 53 then commences to turn back from the position best shown in Fig. 6 to a position where it is hit by the extending trip 57 which draws the pin in to disengage the clutches, and immediately this occurs the spring operates to force the bell crank back to the initial position as shown in Fig. 7. During the interval that the clutch members are engaged the straps are rewinding on the pulleys and the basket is raised and, owing to the action of the weight 44, takes its initial receiving position.

In considering the action of the basket at the time the sheaf is deposited it will be obvious that the basket is free to swing axially at the ball and socket joints to clear the stook and is also free to swing bodily backwardly owing to the fact that the upper ends of the hangers are pivoted to the top frame. This back swinging feature allows the basket to steady the deposited stook for a short interval as it will be borne in mind that the instant the stook touches the ground the machine is moving in respect to it and the back swing allowed the basket accommodates the forward movement of the ma-

chine to allow the basket to stay with the stook a short interval.

After the basket has returned to its normal position the clutch automatically disengages in the manner heretofore disclosed 70 and the basket remains in the up position until the attendant again wishes to dump the stook. The action is then repeated for successive stooks.

In the above description it will be readily understood that various details could be readily modified without departing in the slightest from the spirit of the invention as covered by the appended claims.

What I claim as my invention is:— 80

1. A shocking machine comprising in combination a framework, a pair of vertically disposed side hangers having their upper ends pivotally secured to the framework, a sheaf receiving and shock forming pivoted basket contained within the framework and slidably mounted on the hangers, releasable means holding the basket in the sheaf receiving position at the upper end of the hangers, means for up-ending the basket when released to slide downwardly on the hangers and means for returning the basket to normal position after dumping the stook.

2. A shocking machine comprising in 95 combination a framework, a pair of opposing vertically disposed guide shafts having their upper ends pivotally secured to the framework, a pivoted sheaf receiving and shock forming basket slidably mounted on 100 the guide shafts, releasable means normally holding the basket in an elevated position on the guide shafts and in the sheaf receiving position, means for upsetting the basket to deposit the contained stook and 105 coincident with the dropping of the basket on the guide shafts and means for returning the basket to the elevated sheaf receiving position after dumping.

3. A shocking machine comprising in 110 combination a framework presenting an open upper frame, a pair of opposing vertically disposed guide shafts having their upper ends pivotally secured to the upper frame, a pair of sleeves slidably mounted on 115 the shafts, a pivotally mounted sheaf receiving and shock forming basket contained within the frame and carried by the sleeves, releasable means for holding the sleeves at the upper end of the guide shafts and with 120 the basket elevated, a cross bar engaging with the rear end of the basket and normally holding the same in a horizontal sheaf receiving position, said bar being designed to upset the basket to dump the stook upon 125 the basket being released to drop on the shafts and means for returning the basket to its original sheaf receiving position.

4. A shocking machine comprising in combination a framework, presenting an 130

- open upper frame, a pair of opposing centrally located vertically disposed guide shafts having their upper ends pivotally secured to the upper frame, a pair of sleeves 5 slidably mounted on the shafts, a sheaf receiving and shock forming basket pivotally carried by the sleeves, a normally locked winding appliance holding the sleeves at the upper ends of the shafts and with the basket in sheaf receiving position, means for 10 releasing the winding mechanism to allow the sleeves and basket to drop, a trip bar adapted to engage with the rear end of the basket and upset the same during the dropping 15 action and means for returning the basket to the original sheaf receiving position after dumping the stool.
- 5: A shocking machine comprising in combination a framework presenting an open upper frame, a pair of centrally located vertically disposed guide shafts having their upper ends pivotally secured to the upper frame, a pair of sleeves slidably

25 mounted on the shafts, a sheaf receiving and shock forming basket pivotally carried by the sleeves, a normally locked winding appliance holding the sleeves at the upper ends of the shafts and with the basket in sheaf receiving position, means for releasing the winding mechanism to allow 30 the sleeves and basket to drop, a trip bar adapted to engage with the rear end of the basket and upset the same during the dropping 35 action, a pressure plate located at the front end of the basket, means for forcing the plate inwardly toward the basket during the dumping of the basket and means for returning the basket to the original sheaf receiving position after dumping the stool.

40 Signed at Moose Jaw, this fourth day of March 1918.

CHRISTIAN NYGAARD.
